UNITED STATES PATENT OFFICE.

JOHN LAWSON, OF CENTRAL FALLS, RHODE ISLAND.

YARN-CHANGER FOR DOUBLE-FEED AUTOMATIC CIRCULAR-KNITTING MACHINES.

1,145,375.

Specification of Letters Patent.

Patented July 6, 1915.

Application filed February 3, 1913. Serial No. 745,804.

To all whom it may concern:

Be it known that I, JOHN LAWSON, a citizen of the United States, residing at Central Falls, in the county of Providence and State of Rhode Island, have invented certain new and useful Improvements in Yarn-Changers for Double-Feed Automatic Circular-Knitting Machines, of which the following is a specification.

10 In a co-pending application for patent filed by me in the U. S. Patent Office, Serial No. 703,628, I have shown and described a double-feed circular knitting machine for automatically producing seamless stockings.

15 My present invention relates to yarn-changers for knitting machines of the class above referred to, but more especially, however, to knitting machines in which the needle-carrying cylinders are revolute, and in

20 which the tubular portions of the stockings are knitted from a plurality of independently arranged main threads or "double-feed" knitting, as it may be termed. In knitting-machines of this last-named type

25 the threads are usually introduced at diametrically opposite points and provided with means for knitting both threads simultaneously during certain parts of the stocking.

30 A serious object is to the usual manner of employing a secondary knitting-thread is due to the fact that the thread is kept moving in the plain thread-guide or eye, the thread at the same time also engaging the

35 front of the sinkers and moving back and forth thereagainst when it is thus normally idle or non-knitting, as when the cylinder is reciprocating in producing the heel and toe parts. Such resulting action upon the

40 thread causes excessive wear and abrasion. In case the thread is of fine silk or lisle fiber, the percentage of loss and imperfect product becomes of even greater consideration.

45 The object of the invention forming the subject of this application for U. S. patent is to provide an automatically controlled yarn-changer device for the secondary threads of double-feed knitting machines; the construction and arrangement of said

50 device being such that the yarn-changer is caused to place its thread (the secondary thread) in position for knitting action relatively to the needles at predetermined times concurrently with positioning the corre-

55 sponding knitting cams and sinker-retract-

ing means for such secondary thread. The device is also caused to automatically move the yarn-changer and its thread bodily from said active to the idle or inactive position at fixed intervals, the thread mean- 60 while being held stationary.

My invention is well adapted to be employed in double-feed knitting machines, thereby more rapidly producing the leg portions of plain stockings; it also may be used 65 in knitting the foot portions of plain knitted stockings.

In knitting machines for the production of "split-foot" stockings, wherein the sole of the foot portion is knitted from a heavier 70 or different thread than is used in the upper part, my invention is particularly advantageous in that the yarn-changer and its thread are caused to be automatically moved bodily out of knitting position and held sta- 75 tionary while the cylinder is reciprocating in producing the heel and toe portions from the other knitting thread. At the com- mencement of the "split-foot" part (the cylinder still moving in a reciprocatory 80 manner) the yarn-changer is moved bodily to place its thread downward into knitting position to cooperate with the other knitting-thread or threads; at the same time, too, the secondary knitting and sinker-cams 85 are automatically positioned to convert the last-named thread into courses connecting with the other part of the foot.

In the two accompanying sheets of drawings illustrating my improved yarn-changer 90 connected with certain portions of an automatic circular knitting machine, Figure 1 represents a partial end elevation, viewed from the left, the parts being in the normal knitting position; Fig. 2 is a vertical cross- 95 sectional view, in enlarged scale, taken substantially on line 2-2 of Fig. 3; Fig. 3 is a top plan view, some of the parts being omitted; Fig. 4 is a partial top plan view showing the position of the secondary 100 sinker-cam when the secondary knitting-thread is inactive, and Fig. 5 is a partial side elevation.

It may be stated in advance that the general type of knitting machine represented, except as to the inclusion of improvements, is substantially like that shown in Hemp- 105 hill's U. S. Patent No. 933,443, of September 7, 1909.

The following is a brief description of 110

portions of the said knitting machine, and including a more detailed description of the yarn-changer forming the subject of the present application for patent.

The main frame *a*, together with the top table *a*¹ of the machine have the various knitting instrumentalities mounted thereon; for example, a revoluble needle and sinker-carrying cylinder *N*, a horizontal main cam-shaft *s* arranged to move in the arrow direction in a step-by-step manner, a main cam-block *D* with its knitting-cams, and a normally stationary hinged latch-guard *H* surmounting the needle-cylinder, etc. The latch-guard is extended at the right, said extension being provided with movable yarn-guides *u* for the main thread *t*; said yarn-guides being disposed above the cam-block *D*. A substantially flat plate *B*¹ is located within the needle-row, said plate being secured to the latch-guard and movable bodily with it. The plate *B*¹ may be provided on its upper face with a mechanically actuated yarn-holder or binder *H*² adapted to retain the main thread *t* when the latter is temporarily inactive or floating. The binder device is or may be actuated or controlled by means of an elongated suitably driven slotted lever *k* pivoted to the latch-guard. A thread-severing device having cutting jaws, indicated at *H*¹, Fig. 3, adapted to be actuated by said lever *k* may be employed for obvious purposes.

At a point diametrically opposite the said thread-guides *u* is located my improved independently operable yarn-changer device *A* for the secondary thread *t*¹; see Figs. 1, 2, and 3. The said yarn-changer proper is connected to and capable of movement bodily with the latch-guard; the construction and arrangement being such that the secondary thread may be automatically moved into and out of knitting action at predetermined points while the latch-guard is in the normally dropped position. The yarn-changer *A* is pivoted to a lug *h* of the guard, the thread-carrying end of the former being adapted to swing in a transverse gap or recess *w* formed in the guard *H*. Means represented for moving the yarn-changer to place the secondary thread in knitting position consist of a cam *C*¹ secured to said shaft *s*, said cam having suitable peripherally arranged lugs *f*; these latter, when engaged by the free end *f*¹ of the pivotally mounted lever *l*, in connection with a vertical link *l*² jointed to the opposite end thereof and to the rear end of a swinging horizontal upper lever *l*² impart vertical movement to the guided spring-pressed rod *l*³ vertically supported on the free end of lever *l*². The upper end *l*⁴ of rod *l*³ is beveled or wedge-shape and arranged to engage with and retract the spring-pressed secondary sinker-cam *e* outward concur-

rently with the act of moving the secondary thread downward into knitting position. This last-named movement is effected by means of an arm member *u*³ connected to and extending upward from the rod *l*³ 70 to engage an arm of the yarn-changer *A*. Thus, it will be apparent that the secondary thread is automatically positioned for knitting action whenever the lever *l* bears upon the cam-lugs *f*, and is normally inactive 75 when the shaft *s* in its movements permits the lever to drop from the lugs onto the plain surface or barrel *f*² of the cam *C*¹. A spring *t*³ connected to the yarn-changer causes the latter to automatically place its 80 thread upward out of knitting action (see dotted line position Fig. 2) upon the engagement of the lever *l* with the surface *f*² of the cam *C*¹, a spring *t*⁴ encircling the rod *l*³ serving at the same time to insure the 85 downward movement of the latter.

Means for moving the secondary cam-block *D*¹ toward and from the needle cylinder may be effected by means of a suitably actuated horizontal link *n*⁴ jointed to a pivoted lever *n*⁵, in turn jointed to a cross-head *n*⁶ carrying a pair of guided laterally separated rods *n*⁷ fixed to the block *D*¹, substantially as shown in Figs. 1, 3 and 5.

The secondary knitting-thread *t*¹ is positioned downward for action concurrently with the action of suitably timed mechanism for placing the secondary sinker-cam *e* outward to successively position the sinkers *o* while the thread is introduced to the needles in passing that point. At the same time, too, the mechanism connected with the sliding block *D*¹ moves the latter inward so as to cause its knitting-cams to engage the needles and convert the thread into connected stitches.

The secondary thread *t*¹ is moved out of knitting action through the medium of said spring *t*³ simultaneously with the downward movement of the vertical rod *l*³ and its extension *u*³, said downward movement of the rod *l*³ at the same time permitting the spring *e*¹ to press the secondary sinker-cam *e* inward to its limit and cause the sinkers to travel in a path concentrically with the cylinder at that point. See Fig. 4, which represents the cam and sinkers in the inward position. The mechanism for controlling the movements of the cam-block *D*¹ is timed so as to move the block outward from the needles while the secondary thread is thus inactive.

The inner end portion of the secondary thread *t*¹ (when inactive or floating) may be held or retained by a mechanically actuated binder *H*³ mounted on said plate *B*¹, substantially as represented in Figs. 2 and 3.

The movements of the swinging binder or clamping-arm *H*³ may be effected through the medium of said lever *k* and suitable con-

nections adapted to be actuated by a cam (not shown) on the main cam-shaft *s.*

I claim as my invention:

1. The combination in a knitting-machine, of a revoluble knitting-cylinder provided with needles and sinkers, a pivoted latch-guard normally positioned above the cylinder, a yarn-changer or feeder pivoted to the latch-guard, said yarn-changer carrying a secondary knitting yarn, a radially movable horizontal secondary sinker-cam disposed with respect to the needles and sinkers, means engageable with the yarn-changer and sinker-cam for simultaneously moving them into the respective normal knitting positions, and means for automatically moving the last-named elements to place the secondary yarn in an inoperative position.
2. In an automatic double-feed knitting machine having a revoluble needle and sinker-carrying cylinder, a main yarn-feeder, and instrumentalities adapted to convert a yarn carried by it into knitted courses of stitches, the combination there-with of a suitably mounted movable yarn-changer adapted to carry a secondary yarn disposed diametrically opposite said yarn-feeder, movable knitting-cams located below the yarn-changer, a secondary sinker-cam, means for moving the latter inward and outward, and means for causing the yarn-changer to automatically place its yarn in

knitting position simultaneously with the act of moving said sinker-cam outward.

3. A circular knitting-machine, having, 35 combination, a main cam-shaft, a needle-cylinder provided with needles and sinkers, a movable secondary sinker-cam, knitting-cams and devices coöperable therewith for knitting a secondary yarn, a movable latch-guard, having an open recess therein, a swinging yarn-changer device for the secondary yarn having a member thereof adapted to pass through said recess in placing its yarn in the knitting and non-knitting positions, a clamping-arm H³ movable bodily with the latch-guard for holding the secondary yarn stationary in the non-knitting position while the needle-cylinder is reciprocating, and instrumentalities actuated from said main cam-shaft for automatically placing in the idle or inoperative positions the said secondary sinker-cam, the secondary knitting-cams, and the secondary yarn-changer, and at the same time causing the said clamping-arm to engage and hold the secondary yarn, substantially as described. 50

In testimony whereof I have affixed my signature in presence of two witnesses.

JOHN LAWSON.
